William Burges 9489X

The Schedule referred to in these Letters Patent and making part of the same, containing a description in the words of the said William Burges, of his Improvement in the cast iron Fire place for warming, cooking, baking &c.

To all to whom these presents shall come: Be it known that I, William Burges, of Middleborough, in the County of Plymouth and Commonwealth of Massachusetts, have invented a new and useful improvement in the construction of the "cast iron Fire place", and that the following is a full and exact description of the construction and operation of said Fire place, as invented or improved by me. My improvement consists in applying an oven and cooking apparatus, at the back of the common cast iron Fire place or frame. The front part or frame of my fire place is of the usual form and size of the open fire place or frame; at the back of this I attach an oven of any convenient form and size; this oven may be divided into any number of apartments which may be required for cooking. The oven is heated by means of flues or apertures, leading from the back, or that part of the fire place which comes in contact with the fire, and extending all round the oven. Through these flues and apertures the heat and smoke pass and heat the oven. These flues or apertures I make the whole width of the fire place and about one inch in depth - at the bottom of that part of my fire place which contains the oven, there is an apartment for heating air to assist in warming the room. That part of the fire place which contains the oven and cooking apparatus, may be cast with the fire place, or it may be cast separate and applied to the common fire frame. The particular advantage which this fire place has over most others consists in having an open fire place, together with all the advantage of the most approved close and cooking stoves. Attached to this specification is a drawing of my improvement, and making a part of this specification. What I claim as my improvement, is the application of the oven

and cooking apparatus to the common open fire place or frame as
above described.
